UNITED STATES PATENT OFFICE

BASILIO L. FRATESI, JR., OF TRIBBETT, MISSISSIPPI

PAPER BAG HOLDER

Application filed August 28, 1931. Serial No. 559,977.

This invention relates to a holder for paper bags and the like, the general object of the invention being to provide a rotatable frame having a number of spring actuated bag holding members pivoted thereto for holding the bags in such a manner that a single bag can be withdrawn from a pile of such bags placed in each holder, with means whereby the pile of bags can be easily and quickly placed in the holder.

This invention also consists in certain other features of construction and in the combination and arrangement of the several parts to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is an elevation of the invention.

Figure 2 is a longitudinal sectional view thereof.

Figure 3 is a section on the line 3—3 of Figure 2.

Figure 4 is a perspective view of one of the holders.

Figure 5 is a detail view showing how one of the corner posts is attached to the bottom frame member.

Figure 6 is a view of the top plate and its connection wires.

In these drawings, the numeral 1 indicates the base of the device to which is connected a stationary ball race 2 by the bolt 3 and the lower end of a rod 4 is threaded into said race. A spider 5 has its hub 6 connected with the upper race 7, the balls of the race being shown at 8. A hollow vertically arranged shaft 9 has its lower end connected with the hub and said hollow shaft surrounds the rod 4.

A band 10 has portions connected with the outer ends of the arms of the spider and an upright post 11 has its lower end connected in each corner of the band 10. Upper and lower wire frames 12 are connected with the posts and a plate 13 connects with the top of the hollow shaft 9 and has its corners con-

nected by the links 14 with parts of the upper frame 12.

Vertically arranged wires 15 have their upper ends connected with the frame 12, intermediate portions connected with the lower frame 12 and the lower ends connected with the band 10. Thus I have provided an open work frame of rectangular shape in cross section which is rotatably supported on the base 1.

A bag-holder A is pivotally connected to each member of each of the frames 12 by having eyes 16 formed at the upper ends of the limbs thereof through which a member of each frame 12 passes. A spring 17 carried by each frame 12 engages the limbs of each holder A and acts to hold the same or the bags therein, against the wires 15.

Each member A, preferably formed of a single piece of wire, is bent to form the substantially U-shaped pair of horizontally extending members 18, the outer limbs of which are connected to the vertical limbs 19 of the holder and their inner limbs are connected together by a small inverted U-shaped part 20 which is vertically arranged and acts to engage the lower end of the outermost bag of a pile of bags placed on the members 18.

Intermediate the ends of the limbs 19 are formed horizontal arms 21 which are formed by looping the wire upon itself as shown best in Figure 4. These arms 21 and the members 18 extend inwardly into the frame when the holder is pressed inwardly by the spring 17 and when the holder is empty the bight of the part 20 will engage one of the wires 15 which limits inward movement of the holder.

A wire 22 connects the limbs 19 of each holder together slightly above the arms 21 and this wire also engages the outermost sides of the piles placed in the holder as shown in Figure 1. As shown in Figures 1, 2 and 3, there are four holders at the top of the device and four holders at the bottom thereof, and I prefer to make these holders of different sizes so as to hold different sizes of bags.

As shown in Figure 1, the holder is pulled outwardly so that a pile of bags, shown in dotted lines in Figure 1 can be placed there-

in, and then when the holder is released the spring will move the holder inwardly so that the members 20 and 22 will hold the bags against the wires 15. When it is desired to secure a bag it is simply necessary to seize the top or outermost bag and pull the same upwardly to release it from the holder.

As shown the upper portions of the limbs 19 are bent inwardly as shown at 19' so that 10 the holder can hold a greater number of bags than if the limbs were straight. By rotatably supporting the device on the base it can be turned to bring the bags of the desired size to a position where a bag can be readily 15 taken from its holder.

It is thought from the foregoing description that the advantages and novel features of the invention will be readily apparent. It is to be understood that changes may be 20 made in the construction and in the combination and arrangement of the several parts provided that such changes fall within the scope of the appended claims.

I claim:

25 1. A bag holder of the class described comprising a base, a frame rotatably supported thereby and a plurality of spring-pressed bag holders pivotally connected with the frame, each holder consisting of a pair of 30 limbs the upper ends of which are pivotally connected with the frame, a pair of inwardly extending horizontally arranged U-shaped members, the outer limbs of which are connected with the first mentioned limbs and an 35 inverted vertically arranged U-shaped member connecting the ends of the inner limbs together and extending upwardly.

2. A bag holder of the class described comprising a support, a frame of rectangular 40 shape in cross section rotatably supported on the support, a plurality of holders pivotally connected with the frame and each consisting of a pair of vertical limbs, a pair of horizontally arranged U-shaped members 45 the outer limbs of which are connected with the lower ends of the first mentioned limbs, an inverted U-shaped member vertically arranged and having its limbs connected to the ends of the inner limbs of said U-shaped 50 members, an inwardly extending arm on each first-mentioned limb intermediate the ends of the limb, the upper ends of the first mentioned limbs being pivoted to the frame, said frame having members against which the 55 holder presses the bag, and a cross member connecting the upper parts of the first mentioned limbs of the holder together, and spring means tending to move the holder toward the frame.

60 In testimony whereof, I affix my signature.
BASILIO L. FRATESI, Jr.
